AIR CONDITIONING SYSTEM UTILIZING
REFRIGERATIONSamuel M. Anderson, Sharon, Mass., assignor to
B. F. Sturtevant Company, Boston, Mass.

Application November 17, 1938, Serial No. 240,995

8 Claims. (Cl. 62—6)

This invention relates to air conditioning systems employing refrigeration and relates more particularly to air conditioning systems for passenger vehicles employing mechanical refrigeration.

- 5 The usual air conditioned railway passenger car, is provided with an over-sized refrigerant compressor capable of supplying the refrigeration required under peak load. The compressor prob-
10 ably operates under peak load not more than ten days of a year, although it operates under reduced load about five months of a year. It is also the practice to recirculate about 75% of the air through the air cooler for saving refrigeration.
15 This results in the over-sized compressor being started and stopped by the car thermostat at frequent intervals, it being idle a longer period than it is in service. This frequent cycling of the compressor equipment is undesirable for the
20 reason that it increases depreciation of the equipment. The continuous recirculation of the air also adds undesirable odors to the air.
- I have determined that for a large portion of the time, the wet bulb temperature of the outdoor
25 air is at or below about 70° F. under average conditions. I have also determined that when the wet bulb temperature of the outdoor air is not above about 70° F., the increased cost due to energy consumed, of supplying 100% outdoor air
30 to the cooler, and of operating the compressor during longer periods and in fact, continuously if possible, is more than justified by the absence of unpleasant odors from the air, better control of humidity, and better air conditions.
35 I provide an air washer for cleaning and cooling the air, refrigeration compressor equipment for cooling the spray water, a car thermostat for starting and stopping the compressor, and a wet bulb thermostat in the outdoor air stream for ad-
40 justing the outdoor and recirculated air intake shutters for increasing the volume of outdoor air preferably to 100% when the wet bulb tempera-
45 ture of the outdoor air is at or below 70° F., and for decreasing the volume of outdoor air when the wet bulb temperature of the outdoor air rises above 70° F.

Another feature of my invention resides in automatically reinvigorating the recirculated air
50 when the controls act to supply it to the conditioner. This is accomplished, for example, by irradiating the recirculated air with ultra-violet light for destroying bacteria, and/or by spraying into the recirculated air a substance such, for ex-
ample, as pine oil for the purpose of imparting

to the recirculated air the characteristics of outdoor air.

It is seen therefore that one object of my invention is to use larger volumes of outdoor air in the air conditioning of passenger vehicles, and to operate the refrigerating equipment during longer periods than has been the practice in the past, and that another object of the invention is to reinvigorate the recirculated air to simulate outdoor air when it is not economically feasible to use all outdoor air.

The invention will now be described with reference to the drawing which is a diagrammatic view of one embodiment of the invention.

The air washer 5 is supplied with chilled water 15 by the pump 6 from the evaporator 1. The compressor 8, driven by the electric motor 9, supplies the usual volatile refrigerant to the evaporator, through the condenser 10.

The car thermostat 11 is connected in circuit 20 with the motor 9 and the electric source 12 and starts and stops the compressor motor when the temperature is above and at respectively, the desired temperature.

The blower 13 draws outdoor air through the 25 shutters 14, and recirculated air from the passenger space through the shutters 15, and passes the air through the washer 5 into the supply duct 17.

The shutters 14 and 15 are adjusted by the mo- 30 tor 16 which is controlled by the thermostat 18 which responds to changes in the wet bulb temperature of the outdoor air. The thermostat is connected by the wires 19, 20, 21 and 22 in circuit with the shutter motor 16 and the electric 35 source 12 and acts when the wet bulb temperature of the outdoor air is at and below 68° F., to open the above described circuit causing the motor 16 to close the shutters 15 and open the shutters 14 so that all outdoor air enters the 40 washer 5. During this period, the load on the conditioner is greater and the compressor operates for longer periods of time. The result however, is that the air is more comfortable, is odorless, and the humidity does not rise as it normally 45 does during the more frequent off cycles of the prior systems.

When the wet bulb temperature of the outdoor air is above 70° F., the thermostat 18 closes the above described circuit causing the outdoor and 50 recirculated air shutters to be adjusted by the motor 16 to supply, for example, 75% recirculated air and 25% outdoor air. At the same time, the converter 23 and motor 24 both of which are connected in shunt to the shutter motor 16, are 55

energized. The converter then energizes the ultra-violet lamp 25 in the recirculated air stream, to irradiate the recirculated air for destroying harmful bacteria, and the motor 24 drives the air pump 26 to spray pine oil or other substances simulating outdoor air conditions, from the container 28 through the nozzles 27, into the recirculated air.

While it is preferred that the thermostat 18 adjust the shutters to 100% outdoor air when the wet bulb temperature is below the selected maximum, improved results could also obviously be obtained by decreasing the volume of recirculated and increasing the volume of outdoor air 15 over those ordinarily supplied.

Other methods of reinvigorating the recirculated air could be employed. For example, the motor 24 could be actuated when recirculated air is supplied, to add the pine oil, or other de- 20 sired substance to the washer spray water.

While the invention has been described in connection with mechanical refrigeration, other forms of refrigeration could be employed. The usual ice source could be used and the thermo- 25 stat 11 could operate a by-pass around the ice water supply tank.

While one embodiment of the invention has been described for the purpose of illustration, it should be understood that other apparatus and 30 arrangements of apparatus may be suggested by those skilled in the art without departure from the spirit of the invention.

What is claimed is:

1. An air cooling system comprising an air 35 cooler, means for supplying outdoor and recirculated air into said cooler, a thermostat exposed to outdoor air for adjusting said means for increasing the proportion of outdoor and for decreasing the proportion of recirculated air when the outdoor temperature is below a predetermined point and for increasing the proportion of recirculated air and for decreasing the proportion of outdoor air when the outdoor temperature is above said point, means for reinvigorating the 40 recirculated air to simulate outdoor air conditions, and means for actuating said last mentioned means when said thermostat acts to increase the proportion of recirculated air.

2. An air cooling system comprising an air 50 cooler, means for supplying outdoor and recirculated air into said cooler, a thermostat exposed to outdoor air for adjusting said means for increasing the proportion of outdoor and for decreasing the proportion of recirculated air when the outdoor temperature is below a predetermined point and for increasing the proportion of recirculated air and for decreasing the proportion of outdoor air when the outdoor temperature is above said point, means including an 55 ultra-violet lamp for reinvigorating the recirculated air to simulate outdoor air conditions, and means for actuating said last mentioned means when said thermostat acts to increase the proportion of recirculated air.

65 3. An air cooling system comprising an air cooler, means for supplying outdoor and recircu-

lated air into said cooler, a thermostat exposed to outdoor air for adjusting said means for increasing the proportion of outdoor and for decreasing the proportion of recirculated air when the outdoor temperature is below a predetermined point and for increasing the proportion of recirculated air and for decreasing the proportion of outdoor air when the outdoor wet bulb temperature is above said point, means including means for adding a pleasant odor to the air for 10 reinvigorating the recirculated air to simulate outdoor air conditions, and means for actuating said last mentioned means when said thermostat acts to increase the proportion of recirculated air.

4. An air cooling system comprising an air 15 cooler, means for supplying outdoor and recirculated air into said cooler, a thermostat exposed to outdoor air for adjusting said means for increasing the proportion of outdoor and for decreasing the proportion of recirculated air when the outdoor temperature is below a predetermined point and for increasing the proportion of recirculated air and for decreasing the proportion of outdoor air when the outdoor temperature is above said point, means including 20 an ultra-violet lamp for irradiating the recirculated air and including a device for adding a pleasant odor to the air for reinvigorating the recirculated air to simulate outdoor air conditions, and means for actuating said last mentioned means when said thermostat acts to increase the proportion of recirculated air.

5. An air conditioner comprising a heat ex- 25 changer having an outdoor and a recirculated air inlet, an ultra-violet lamp for irradiating the recirculated air, an energizing source for said lamp, temperature responsive means for closing the recirculated air inlet, and means actuated when said temperature responsive means closes said recirculated air inlet for disconnecting said lamp from said source.

6. An air conditioner comprising a heat ex- 30 changer having an outdoor and a recirculated air inlet, an ultra-violet lamp for irradiating the recirculated air, an energizing source for said lamp, 45 an outdoor wet bulb thermostat for closing the recirculated air inlet when the wet bulb temperature of the outdoor air falls below a predetermined point, and means actuated when said thermostat closes said recirculated air inlet for disconnecting said lamp from said source.

7. An air conditioner comprising a heat ex- 40 changer having a recirculated air inlet, means for varying the volume of recirculated air entering said inlet, a device for adding a pleasant odor to the air, and means for actuating said device when said first mentioned means increases the 55 volume of recirculated air.

8. In a heat exchanger having an outdoor air 60 inlet, means forming a recirculated air inlet into said conditioner, adjustable means for opening and closing said recirculated air inlet, a device for adding a pleasant odor to the air, and means for actuating said device when said adjustable means opens said recirculated air inlet.
